[57] CLAIM

The ornamental design for a wall-mounted display rack,
substantially as shown and described.

DESCRIPTION

FIG. 1 is a perspective view of a wall-mounted display
rack showing my new design;

FIG. 2 is a left side elevational view thereof;

FIG. 3 is a bottom plan view thereof;

FIG. 4 is a perspective view shown broken away to
indicate indeterminate length; and

FIG. 5 is a left side elevational view shown broken
away to indicate indeterminate length.
